the novel relationship of said jaws and the novel manner of using said jaws which will permit the use of a gage which is of simple, sturdy construction and which will maintain its adjustment throughout long periods of use.

UNITED STATES PATENT OFFICE

2,562,124

SNAP GAUGE

Jan Reef, Detroit, Mich.

Application February 26, 1945, Serial No. 579,807

2 Claims. (Cl. 33—168)

1 This invention relates to improvements in gages.

The instant gage is what is termed in the parlance of the trade a "go" "no go" gage. It comprises a U-shaped frame the ends of which are provided with opposed jaws which are relatively adjustable toward and away from each other and between which a part is inserted to gage the dimension of said part. One jaw is divided into two sections disposed in side by side relationship for independent slide adjustment within a guide way formed in one end of the frame. One jaw section is normally projected to approach nearer to the opposed jaw than the other jaw section whereby a part to be gaged may be received between said other jaw section and the opposed jaw but such part to be gaged will not enter the space between the opposed jaw and said projected jaw section.

An object is to provide a gage of the character described wherein novel means is provided to advance or withdraw an adjustable jaw within a guide. A further object is to provide a gage having adjustable jaws and means operable to adjust and maintain the jaws at adjusted position which adjustable jaws and means are so disposed as to be protected against being accidentally struck and thereby possibly displaced.

Another object is to provide a gage of the character set forth which is of simple, sturdy construction and wherein the gaging jaws may be readily adjusted and will maintain their adjustment throughout long periods of use.

Other objects, advantages and meritorious features will more fully appear from the following description, appended claims and accompanying drawing, wherein:

Figure 1 is a plan of a gage embodying the invention.

Figure 2 is a cross sectional view taken on the line 2—2 of Figure 1.

Figure 3 is a cross sectional view taken on the line 3—3 of Figure 2.

Figure 4 is a cross sectional view taken on the line 4—4 of Figure 3.

Figure 5 is a perspective of one of the jaw sections.

Figure 6 is a cross sectional view taken on the line 6—6 of Figure 1.

The gage illustrated in the drawing comprises a U-shaped body or frame 10. Each end of the frame is provided with a guide way 12. Within the guide way at one end of the frame is mounted a jaw 14. Within the guide way of the other end of the frame a pair of jaw sections 16 and 18

are novelly related in such a manner as to provide a gage which will permit the use of a gage which is of simple, sturdy construction and which will maintain its adjustment throughout long periods of use.

Figure 1 shows the gage 10 in a plan view with the jaws 14 and 16 and 18 in their normal positions. Figure 2 shows the gage 10 in a cross section with the jaws 14 and 16 and 18 in their normal positions. Figure 3 shows the gage 10 in a cross section with the jaws 14 and 16 and 18 in their normal positions. Figure 4 shows the gage 10 in a cross section with the jaws 14 and 16 and 18 in their normal positions. Figure 5 shows a perspective of one of the jaw sections 16 and 18. Figure 6 shows a cross section of the jaw section 16 and 18.

2 This invention relates to improvements in gages.

The instant gage is what is termed in the parlance of the trade a "go" "no go" gage. It

comprises a U-shaped frame the ends of which

are provided with opposed jaws which are

relatively adjustable toward and away from each

other and between which a part is inserted to

gage the dimension of said part. One jaw is

divided into two sections disposed in side by side

relationship for independent slide adjustment

within a guide way formed in one end of the

frame. One jaw section is normally projected

to approach nearer to the opposed jaw than the

other jaw section whereby a part to be gaged

may be received between said other jaw section

and the opposed jaw but such part to be gaged

will not enter the space between the jaw section 16

and the opposed jaw 14. The gage therefore constitutes what was

above referred to as a "go" "no go" gage.

In the gage here shown each of the jaw ele-

ments is capable of adjustment toward and away

from the opposed jaw element. Each adjustable

jaw element carries a screw 20 which is threaded

thereto, as shown in Figure 6 and which screw

extends through a slot 22 formed in the end of

the frame as shown in Figures 1 and 3. This slot

is undercut as at 24 so that the head of the

screw may be tightened down against such under-

cut portion and draw the jaw securely against

the bottom of the guide way 22 as shown in

Figure 4 to provide for holding the adjustable

jaw elements at adjusted positions with respect

to each other.

Each guide way underneath an adjustable jaw

is provided with a recess 26. An adjustment

screw 28 is threaded into a threaded aperture in

the bottom of this recess. The screw extends

lengthwise of the recess which recess extends

lengthwise of the direction of permitted adjust-

ment of the jaw. Each adjustable jaw is pro-

vided with a cutout or groove 30 formed in its

under surface as shown in Figure 5. The head

32 of the adjustment screw 28 is revolvably re-

ceived within the groove 30 so that when the

screw is threaded in or out with respect to the

recess 26 the jaw is advanced or withdrawn with

the screw.

Upon removal of the cover plate 34 access is

obtained to screws 28 to rotate them. Each jaw

is normally held by its screws 20 against the bot-

tom of its guide way but upon loosening its screws

20 a jaw may be advanced or withdrawn with re-

spect to the opposed jaw member through rota-

tion of its adjustment screws 28. When the prop-

er adjustment has been made the cover plate 34 is

replaced and fastened down by the screws 36. It

is apparent that in the construction shown any one of the three jaw elements may be advanced or withdrawn with respect to the opposed jaw elements.

Each of the three jaws 14, 16 and 18 is shown in Figures 2, 4 and 6 as provided with a shoulder 15 extending along its gauging edge portion which shoulder projects beyond that face of the frame within which the jaws are slidably disposed, when such jaws are received within the channel recess of a piece of work with the outer faces of the jaws opposed to one side wall of the channel the shoulders 15 of the jaws alone engage a side wall of the channel, thereby minimizing the friction and reducing danger of error due to irregularity of the surface of the work. Such part to be gauged might constitute a portion of a structure which was of a size that would prevent entrance of the part between the arms of the frame, but because of the projection of the shoulders beyond the plane of the arms, the part to be gauged could be entered between the shoulder portions of the jaws even though the structure would not enter between the arms.

The gauging edge portions of the jaws might exhibit any desired contour, as for example any desired radius or bevel to be received within any shape of groove of part to be gauged.

What I claim is:

1. A gage comprising a U-shaped frame, aligned channel guide ways transversely disposed in the side faces of the outer ends of the arms, each arm having a bore extending transversely therethrough parallel to said guide way and in superposed relation thereto, each bore being counterbored from the outer side of said arm throughout a portion of its length, the radius of the counterbore being greater than the distance from the center of said bore to the bearing surface of the bottom of said guide way whereby the counterbore throughout its length communicates with the bottom of the guide way and forms a slot therein, said bore being internally threaded along the remainder of its length, an adjusting screw received within the threaded portion of each bore having a head conforming to the size of the counterbore and received therein whereby said head projects through said slot into the bottom of said guide way, a jaw slidably mounted in each guide way, and means for retaining the same therein, each jaw having a transversely disposed groove adjacent one end receiving the head of the adjacent screw whereby rotation of the same moves the jaw along the guide way, each jaw retaining means comprising a slot in the frame arm extending in the direction of jaw movement and

communicating with the bottom of the guide way, and a headed screw extending through said slot and threaded into an opening in the jaw.

2. A gage comprising a U-shaped frame, aligned channel guide ways transversely disposed in the side faces of the outer ends of the arms, each arm having a bore extending transversely therethrough parallel to said guide way and in superposed relation thereto, each bore being counterbored from the outer side of said arm throughout a portion of its length, the radius of the counterbore being greater than the distance from the center of said bore to the bearing surface of the bottom of said guide way whereby the counterbore throughout its length communicates with the bottom of the guide way and forms a slot therein, said bore being internally threaded along the remainder of its length, an adjusting screw received within the threaded portion of each bore having a head conforming to the size of the counterbore and received therein whereby said head projects through said slot into the bottom of said guide way, a jaw slidably mounted in each guide way, and means for retaining the same therein, each jaw having a transversely disposed groove adjacent one end receiving the head of the adjacent screw whereby rotation of the same moves the jaw along the guide way, each jaw retaining means comprising a slot in the frame arm extending in the direction of jaw movement and communicating with the bottom of the guide way, and a headed screw extending through said slot and threaded into an opening in the jaw, said slot being undercut on the side opposite the jaw for reception of the head of the screw to a depth substantially equal to the thickness thereof.
